UNITED STATES PATENT OFFICE.

CONRAD H. ZIERDT, OF ROSEDALE, PENN TOWNSHIP, ALLEGHENY COUNTY, PENNSYLVANIA, ASSIGNOR TO THE UNION SWITCH AND SIGNAL COMPANY, OF SWISSEVALE, PENNSYLVANIA, A CORPORATION OF PENNSYLVANIA.

TRAIN-CARRIED RECEIVER FOR AUTOMATIC TRAIN-CONTROL SYSTEMS.

Application filed October 5, 1925. Serial No. 60,504.

My invention relates to automatic train control systems of the type wherein train carried apparatus is controlled at least in part by an alternating current which flows through the two track rails in multiple. More specifically, my present invention relates to a train carried receiver for use in systems of this character.

One object of my invention is the provision of a receiver which will supply energy to the train carried apparatus in accordance with the train controlling current in the track rails, but which will not supply energy to such apparatus in accordance with alternating currents flowing in adjacent transmission lines or in adjacent tracks, etc.

I will describe one form of receiver embodying my invention, and will then point out the novel features thereof in claims.

In the accompanying drawing, Fig. 1 is a diagrammatic view showing a portion of an automatic train control system including one form of receiver embodying my invention. Fig. 2 is a front view of the receiver A shown in Fig. 1.

Similar reference characters refer to similar parts in each of the views.

Referring first to Fig. 1, the reference characters 1 and 1^a designate the track rails of a railway, which rails are divided by insulated joints to form a track section. Connected across the rails of this section at spaced points are two resistances 3 and 3^a, and connected with the middle points of these two resistances respectively are the two terminals of the secondary 4 of a transformer T. The primary 5 of this transformer is supplied with alternating train controlling current from a suitable source not shown in the drawing. It is understood that in practice the supply of current to the track rails by transformer T will usually be controlled in accordance with traffic conditions, but inasmuch as the controlling means forms no part of the present invention it is omitted from the drawing. It will be apparent that the current supplied by transformer T flows through the two track rails 1 and 1^a in multiple, that is, at any given instant it flows in the same direction in these rails.

The reference character W designates a railway train provided with a receiver A

embodying my invention. Referring to Fig. 2, this receiver A comprises a bar 8 of magnetizable material extending transversely across the two track rails 1 and 1^a, which bar is provided with four downwardly projecting legs 9, 10, 11 and 12. These legs are so disposed that the legs 9 and 10 are on opposite sides of one track rail 1^a, whereas the legs 11 and 12 are on opposite sides of the other track rail 1. The two inner legs 10 and 11 are provided respectively with feet 10^a and 11^a which extend parallel with the track rails, as shown more clearly in Fig. 1. The four legs 9, 10, 11 and 12 carry a winding which is made up of four coils 13, 14, 15 and 16, located upon the four legs respectively. This winding is included in a pick-up circuit B, the four coils being connected in series in this circuit in such manner that the polarities of the coils on each two adjacent legs are opposite. The pick-up circuit also includes a condenser 7 which will usually be adjusted to balance the inductive impedance of the circuit B, so that this circuit is tuned to resonance at the frequency of the current furnished by transformer T.

The pick-up circuit B may be used in connection with train carried governing apparatus of any suitable type. As here shown, this circuit supplies energy to one winding 4 of an induction motor relay R, the other winding 5 of which is supplied with energy by any suitable means having nothing to do with the present invention. An amplifier is preferably interposed between the receiving circuit B and the winding 4. As here shown, the amplifier is connected across the terminals of the condenser 7.

The magnetic fluxes surrounding rails 1 and 1^a due to the current from transformer T in these rails, may be represented by the broken lines 17 and 17^a in Fig. 2. The flux 17 surrounding rail 1 will pass through coils 15 and 16 in such directions as to create electromotive forces in the circuit B which are additive. Similarly, the flux 17^a surrounding rail 1^a will flow through coils 13 and 14 in such directions as to create electromotive forces in the circuit B which are additive. Furthermore, the electromotive forces thus created in coils 15 and 16 by the one flux and in coils 13 and 14 by the other flux are additive. An electromotive force is therefore

created across the terminals of condenser 7 due to current supplied to the track rails by the transformer T.

The two rails will also be surrounded by a magnetic flux which may be represented by the broken line 18. This flux will flow through the coils 13 and 16 in such directions as to create electromotive forces in these coils which are additive to each other, and which are also additive to the electromotive forces created by the fluxes 17 and 17^a surrounding the individual rails.

A horizontal foreign magnetic flux will pass partly along the bar 8 and so will create no electromotive force in the winding of receiver A. A part of such flux will enter at the leg 9, and will leave at legs 10, 11 and 12, while another part will enter at leg 10 and will leave at legs 11 and 12. A very small part may enter at leg 11 and leave at leg 12. By proper balancing of the turns in the several coils and of the sizes of the feet 10^a and 11^a, the parts of a horizontal flux which actually pass through the coils may be made to substantially neutralize each other and so to create no substantial electromotive force in circuit B.

A vertical foreign flux will pass through all four legs of the core in the same direction, and by properly selecting the number of turns in the coils and the size of the feet, the resulting electromotive forces created in the pick-up circuit B can be made nearly equal and opposite.

It follows from the foregoing, that any foreign magnetic flux due to alternating current in a transmission line or an adjacent track, will create little or no electromotive force in the pick-up circuit B and so will have little or no tendency to cause false operation of the train governing relay R.

In a train control system of the type to which this invention relates, the receiver A is usually located between the engine and tender of a steam train, and between the first and second cars of an electric train. I have found that in some instances a portion of the current from transformer T will leave the rails at the forward end of the train, pass through the steel structure and couplers

of the train and return to the rails from the rear end of the train. Inasmuch as the receiver A is usually located under a coupler, it follows that this current which passes through the train itself, and which is usually termed the "coupler" current, will pass above the receiver A. When the receiver is constructed in accordance with my invention, the magnetic flux surrounding the coupler will pass through the middle legs 14 and 15 of the receiver core 8, and so will create voltages in the coils 14 and 15 which assist the voltages induced in the circuit B by the current which remains in the track rails.

Although I have herein shown and described only one form of receiver embodying my invention, it is understood that various changes and modifications may be made therein within the scope of the appended claims without departing from the spirit and scope of my invention.

Having thus described my invention, what I claim is:

1. A train-carried receiver comprising a bar extending transversely across the track rails and having four downwardly projecting legs two of which are on opposite sides of one track rail and the other two of which are on opposite sides of the other track rail, and a winding made up of a coil on each leg, said coils being connected in series in such manner that the electromotive forces induced therein by an alternating current flowing through the two track rails in multiple are additive.

2. A train-carried receiver comprising a bar extending transversely across the track rails and having four downwardly projecting legs, two of which are on opposite sides of one rail and the other two of which are on opposite sides of the other rail, the two inner legs having feet extending parallel to the track rails, and a winding made up of a coil on each leg, said coils being connected in series in such manner that the electromotive forces induced therein by alternating current in the track rails are additive.

In testimony whereof I affix my signature.

CONRAD H. ZIERDT.
